(57) **CLAIM**

The ornamental design for an inflatable towable vehicle, as shown and described.

DESCRIPTION

FIG. 1 is a perspective view showing my new design; FIG. 2 is a top plan view thereof;

FIG. 3 is a front elevation view thereof;

FIG. 4 is a left side elevation view thereof;

FIG. 5 is a right side elevation view thereof;

FIG. 6 is a rear elevation view thereof; and,

FIG. 7 is a bottom plan view thereof.

The broken lines illustrate stitching and portions of the inflatable towable vehicle. None of the broken lines form part of the claimed design.

1 Claim, 3 Drawing Sheets(56)
